WIND DRIVEN PROPELLER FOR BOATS

Robert J. Annis, Portland, Oreg.

Application November 19, 1952, Serial No. 321,481

7 Claims. (Cl. 115—3)

1

This invention relates to improvements in sails for boats and is particularly adapted to be used in connection with boats that are to be propelled by the winds.

The primary object of the invention is to construct a wind driven reaction turbine sail that will drive a propeller by the power of the wind.

Another object of the invention is to construct a sail that is confined within a very close area to the mast of the boat, but still providing the greatest amount of sail reaction to the wind.

A still further object of the invention is to spread or furl the sail by the power of the wind in addition to manual control.

Another object of my new and improved turbine sail construction is that anyone with a limited experience can operate the same.

Another object of the invention is that the boat can be propelled in any desired direction with complete control regardless of wind direction.

With my new and improved turbine sail construction sudden changes in the direction of the wind has no effect on the propulsion of the boat.

Further, any pitching of the boat in rough water tends to add to the propelling of the boat by the action of my sail, which in the case of ordinary sails, propelling power is lost.

These and other incidental objects will be apparent in the drawings, specification and claims.

Referring to the drawings:

Figure 1 is a plan view of my new and improved turbine sail mounted to a boat.

Figure 2 is a side view of Figure 1, part of the boat broken away for convenience of illustration.

Figure 3 is an enlarged detail view of the mast and sail construction, parts broken away for convenience of illustration.

Figure 4 is an enlarged detail of one of the tips of the spider-like tubular curved spars, parts broken away for convenience of illustration.

Figure 5 is an enlarged plan sectional view, taken on line 5—5 of Figure 3.

Figure 6 is an enlarged detail fragmentary sectional view, taken on line 6—6 of Figure 5.

Figure 7 is a plan sectional view, taken on line 7—7 of Figure 3, illustrating the method of attaching the sails to the lower part of the mast.

Figure 8 is the same as Figure 6, except that the driving mechanism for spreading the sail or furling the same is shown in operating position.

Referring more specifically to the drawings:

My new and improved reaction turbine sail 55

2

for boats consists of a mast 1, rotatably mounted to the hull 2 of the boat by a stationary stub mast 3 by way of the bearings 4 and 5. The bearing 5 supports the weight of the mast upon the shoulder 6 of the stub mast as best illustrated in Figure 3. Fixedly secured to the top of the mast are multiple spars 7. Each of the spars are curved as shown in Figure 1 to form the aerofoil of the sail.

I will now describe how the sails are rigged to the spar arms and to the mast. The sails are indicated by numeral 8. These sails are formed in a somewhat triangle shape, the top of the sail being the base of the triangle, the top of the sail is secured to the spar arms by the rings 9 by the ropes 10, which are sewed between a double sail cloth coming to a point at the apex of the triangle at 11, at which point the ropes terminate in a special fitting or clew 12. This clew or fitting is then connected to the mast by the segmented clamp ring 13, by clamping the clew between the ears 14 of the said rings by way of the bolt 15.

My sail is controlled in regards to furling or unfurling by the ropes 16, which are trained about pulleys 17 journaled within the outer ends of the spars by way of the spindles 18 and the pulleys 19 and 20, which are journaled within the hub of the spar arms, as best illustrated in Figures 3 and 4. Extending downwardly from the upper runs 21 of the ropes 16 and over the pulleys 19 are the ropes 21A which terminate in a fitting or bridle 22. This bridle is connected to a compensating spring 23, which in turn is connected to the rope 24, which is wound about the winding drum 25.

The lower run 16A of the rope 16 is brought about the pulleys 20 into the run 16B to the fitting or bridle 27 tying into the rope 24. The compensating spring 23 keeps the upper and lower run of the rope 16 in a taut condition at all times. The sail is connected to this rope, as best illustrated in Figure 4, wherein the outermost ring 9A is connected to the same wherein the rope may pass through an eye 28 and knotted or otherwise secured thereto. The innermost ring 9B is fixedly connected to the spar by a suitable clamp 29.

The drum 25 is keyed to the shaft 31, which is journaled within the bearings 30. The shaft 31 is rotated in either direction by the friction wheels 32, which are keyed to the same as indicated at 33. A brake shoe 34 in the form of a disk, forms part of the splined hub 35. The splines 36 of the hub cooperate with the splines

37 formed on the extension of the bearings 30, forming part of the mast, thereby preventing the brake shoe from revolving.

The spring 38 bears against the shoulder 39 of the hub 35 and maintains the brake surface 40 of the brake shoe against the inner surface 41 of the friction wheel 32, preventing the same from turning when the sail is either furled or unfurled, holding the same in either position.

The drum 25 is caused to rotate in either direction by the friction wheels 32. A non-rotating drum 42 is slidably mounted to the mast 1 as best illustrated in Figures 3, 6 and 8, and is prevented from rotation by the spline-way 43 located within the upper end of the stub mast 3. The drum 42 has a friction surface 44 at its top and a friction surface 45 at its bottom, which is adapted to contact the friction surface 46 of the friction wheels 32 in the following manner.

A lever 47 is pivotally mounted to the upper end of the stub mast at 48 and extends inwardly to the socket 49 formed within the hub 50 of the drum 42. Slidably mounted within the end of the shaft 31 is a plunger or push rod 51. The outer end 52 of the said push rod is adapted to cooperate with the annular sloping surfaces 53 and 54, encircling the inner wall of the drum.

A cross pin 55 passes through the push rod adjacent its inner end, passing through slots 56 formed within the end of the shaft 31. The extremities of the cross pin 55 engage the shoulder 57 formed within the hub 35 of the brake shoe 34. When the plunger is forced inwardly the cross pin 55 forces the brake shoe away from the inner surface 41 of the friction wheel 32, releasing the same and permitting the same to be rotated.

When the lever 47 is operated to either raise or lower the drum 42, either the sloping surface 53 or 54 will release the brake shoe as above described, but at the same time either the friction surfaces 44 or 45 of the drum will contact the friction surface 46 of the friction wheel 32 and as the mast is being rotated by the sail, the friction wheels will be rotated due to the fact that they are being revolved about with the mast 1, and the drum 42 is being held stationary by the stub mast 3. This in turn will revolve the drum 25 reeling and unreeling the rope 24, pulling in the rope 16 in a direction to either furl or unfurl the sail.

In the event it is desired to rotate the drum 25 by hand, slots or openings 58 are formed parallel to the cam surfaces 53 and 54 within the drum so that a crank 59, illustrated by broken lines, can be inserted into the squared socket formed in the outer end of the plunger or push rod 51, as best illustrated in Figure 6. By slightly pushing in on the crank when applying the same, the brake shoe can be released, permitting the crank to rotate the drum 25.

As the mast 1 is revolved it drives the propeller 60 from a reversible transmission 61, of any suitable design. A driving shaft 62 is keyed to the lower end 63 of the mast 1 and is journaled within the bearing 64 of the transmission 61. As the mast 1 is revolved, always in one direction, the shaft 62 transmits this power into the transmission 61, which will be set to drive the boat either forward or backward.

I will now describe the operation of my new and improved reaction turbine sails for boats. Referring to Figure 1, we will assume the direction of the wind is in the direction of the arrows. The wind striking the concave surface of

the sail 65 will rotate the mast clockwise. The wind striking the convex surface of the sail 66 will tend to deflect from the same, allowing the much greater force or pressure developed within the concave surface of the sail 65 to rotate the mast. The wind being trapped within the concave surface of the sail 65 will tend to escape past the mast into the concave surface of the sail 66, causing a reactive power or push behind the said sail 66 from the wind deflected from the sail 65, assisting in the rotation of the mast.

I will now describe the furling and unfurling of the sails. When the lever 47 is lowered it will raise the drum 42, causing the friction surface 45 to engage the friction wheel 32, revolving the same in a direction to wind the rope 24 in a direction to pull the bridle or fitting 27 towards the drum, together with the cables 16B, pulling the lower run 16A of the cables or ropes 16 towards the mast, together with the sail supporting ring 9A, thereby furling the sail. The power of rotation of the mast, of course, transmitting the rotating power to the drum 25.

When it is desired to unfurl the sail, the lever 47 is raised causing the friction surface 44 of the drum 42 to rotate the friction wheel 32 in a direction to revolve the drum 25 so as to wind the cable or rope 24 in a direction to pull the cables 21A and the upper run 21 of the ropes 16 towards the mast over the pulley 17, pulling the lower run 16A towards the pulley 17 and outer end of the spar together with the ring 9A and sail to the position illustrated in the drawings, Figures 1, 2, 3 and 4.

When the sail has either been furled or unfurled, the lever 47 is brought to a neutral position as illustrated in Figure 3. This allows the push rod 52 to enter between the cam surfaces 53 or 54, allowing the spring 38 to apply the brake shoe 34 to the friction wheel surface 41 of the friction wheel 32, locking the same and preventing the drum 25 from rotating, thereby holding the sail either in furled or unfurled position.

The forcing of the end 52 of the push rod 51 into the position illustrated, referring to Figure 6, holds the drum 42 in a neutral position or its friction surfaces 44 and 45 away from the friction drum 32 so that as the sail is being revolved, driving the propeller 60, there will be no rotation transmitted into the drum 25 until the lever 47 is operated, as above described.

In the event that the mast is not in rotation, and it is desired to furl or unfurl the sail, a crank indicated by broken lines 59, is inserted into the end of the push rod 51 through one of the openings 58. The operator forces the rod inwardly, releasing the brake, then revolving the shaft 31 by the crank, together with the drum 25, furling or unfurling the sail.

What I claim is:

1. A boat comprising a hull, a mast structure rotatably mounted on said hull, a propeller journaled on said hull and drivingly connected with said mast structure, radially disposed arms on said mast structure, sails slidably supported by said arms to be retracted against said mast structure when not in use and to be extended during use to form rotor blades for rotating said mast structure to drive said propeller, a drum journaled on said mast structure, two lines attached to the outer edge portions of each of said sails and trained along said arms and said mast structure and wound on said drum, a drive wheel fixed with said drum, a pair of relatively fixed non-rotatable flanges slidably mounted on opposite sides

of said wheel, and means for sliding said flanges to engage one of said flanges with said wheel to drive said wheel by rotation of said wheel with said mast structure.

2. A boat as defined in claim 1 comprising means for releasably holding said wheel against rotation, and cam means on said flanges for releasing said holding means when said flanges are moved into engagement with said wheel.

3. A boat as defined in claim 2 wherein a crank is insertable between said flanges for releasing said holding means and manually driving said wheel.

4. A boat as defined in claim 3 wherein the lines from each of said sails are respectively connected to a pair of bridles, and a single line is wound on said drum and connected at its ends to said bridles, one end of said drum line being connected to its b ridge by a resilient member to maintain said lines under tension.

5. A boat as defined in claim 4 wherein said arms and mast structure are hollow and said drum is journalled within said structure

with said lines extending through said arms and mast structure.

6. A boat as defined in claim 5 wherein said sails are triangular and have one base of the triangle disposed along said mast structure with the other base of the triangle slideable along said arms, the lower apices of said sails being secured to said mast structure.

7. A boat as defined in claim 6 wherein said arms are arcuate to form said sails as arcuate blades.
